WRITING BOARD LAMP AND PAPER HOLDER

Arthur G. Marschat, Whitestone, N. Y.

Application May 29, 1951, Serial No. 228,799

3 Claims. (Cl. 240—2)

1

This invention relates to a writing board lamp. It is an object of the invention to provide a lamp adapted for attachment to a writing board of a type such as used in taxicabs, delivery trucks and in like places where there is an urgent need at many times for a light to be available for writing on the board and whereby the operator does not need to bend or stretch to find adequate lighting for the board and can thus keep himself in an upright position to observe the road.

It is another object of the invention to provide a detachable lamp for a writing board which is so constructed as to contain a pencil and wherein the locating of the pencil in the attachment will automatically turn off the lamp and the removal of the pencil automatically turn on the lamp, in order to keep a pencil at all times available for the user of the writing board, the user of lamp thus being signaled whether or not the pencil is in or out of the lamp.

It is another object of the invention to provide in a lamp attachment for a writing board a simple means for the connection of the attachment to the sides of the board that will permit the attachment to be turned up to release the paper but which, as the attachment is turned down, will retain the paper upon the board, this means of attachment being movable over center between its two positions with respect to the attaching arms that fix the attachment to the board.

Other objects of the invention are to provide a writing board lamp which is of simple construction, inexpensive to manufacture, is formed of standard stock parts, has a minimum number of parts, and is compact, durable and efficient in operation.

For other objects and a better understanding of the invention, reference may be had the following detailed description taken in connection with the accompanying drawing in which:

Fig. 1 is a perspective view of a writing board with the lamp embodying the features of the present invention attached thereto and adjusted to retain the paper upon the board.

Fig. 2 is an enlarged longitudinal sectional view of the board and the attachment taken on line 2—2 of Fig. 1.

Fig. 3 is an enlarged sectional view of the attachment and the board taken generally on line 3—3 of Fig. 2.

Fig. 4 is a bottom planed view of the attachment.

Fig. 5 is an illustrated view showing the manner in which the attachment is pivoted upwardly to release the paper from the board.

2

Fig. 6 is a fragmentary illustrated view on a large scale to show the position of the attaching arms when the attachment is lifted to the position shown in Fig. 5 and showing the point which holds the paper elevated from the board.

Fig. 7 is a fragmentary view of a modified form of the switch which may be used in the attachment and which is operated by a pencil.

Referring now to the figures, 10 represents a writing board adapted to receive a piece of paper 11 upon which writing is to be made. The board 10 affords a smooth top surface so that writing with a pencil 12 upon the paper 11 will be effected in a smooth manner and without the paper being punctured by the pencil point.

According to the invention a lamp attachment indicated generally at 13 has been provided which can be secured to the top edge of the board 10 by projections or arms extending over the sides 15 of the board near the top edge thereof, and in such a manner that the lamp can be pivoted upwardly to release the paper 11 or when pivoted downwardly onto the board it serves to hold the the paper in a fixed manner thereupon. This same attachment 13 serves to support pencil 12 and this pencil may serve to operate a switch which will control the light bulb within the attachment.

The lamp attachment comprises generally a main tube 14 formed of transparent plastic material, such as Lucite and a pencil tube 15 adapted to receive the pencil 12 and cemented or otherwise secured to the side of the lamp tube 14.

The lamp tube 14 has an end plug 16 which contains a lamp socket 17. Cable wires 18 extend through the plug 16, one of which connects with the lamp socket 17 as indicated at 20, and the other of which connects with a sleeve contact as indicated at 21. This sleeve contact lies in the wall of the tube 14. A switch contact 22 is sidable through the sleeve 21, and when released by pencil 12, on the pencil 12 being taken from tube 15, will engage the side of the socket 17 so as to establish a circuit through the socket to light the elongated lamp bulb 23. The contact 22 is connected to a lever 24 pivoted at 25 to the interior of the tube 15. A compression spring 26 urges the lever 24 upwardly at the end which is engaged by pencil 12 and downwardly at the contact ends 22 whereby upon removing the pencil the contact 22 will be forced through the contact sleeve 21 and against the socket 17. The ends of the pencil tube 15 are cut away as indicated at 27 and 28 to provide easy access to the pencil so that it can be easily pushed out of one end of the tube or the other.

50
55

In the opposite end of the lamp tube 14 is a plug 29 which carries an adjustable hook attaching arm or member 30. This attaching arm has a hook portion 34 which extends over the edge of the board 10 and engages with the underside thereof. A spring 35 is provided on the arm 30 to urge the hook portion 34 against the side edge of the board 10. An enlargement 36 is provided on the arm against which the spring 35 may react. It will thus be seen that the board can vary slightly in width and the attachment can be adapted to it. On the lamp plug end of the tube 14 is a fixed hook arm 37 which fits over the opposite edge of the board 10. The cable wires 13 has a plug 39 thereon to fit the outlet socket of the vehicle and to establish an electric connection of the attachment with the vehicle battery.

There is a certain amount of give to the hook arm 30 and hook arm 37 to spring down the attachment upon the board. Legs 41 and 42 serve as a pivot on which the attachment can be rotated upon the board 10. The lower ends of the legs 41 are flat as indicated at 43, in Fig. 6, so as to stabilize the attachment when in the raised position. The attaching arms 30 and 37 are shown tilted to hold the attachment flat upon the bottom faces 43 of the legs 41 and 42 when in the raised position. As the attachment is pivoted down on to the board and into the position shown in Figs. 1 and 2, the projecting arms 30 and 37 will be tilted forwardly and paper engaging points 45 and 46 will be brought into engagement with the paper 11. The spring arms 30 and 37 will forcibly hold the attachment in a position which is shown in Fig. 1 with the parts 45 and 46 entering the paper. These arms will be in tilted position and the leg elements 41 and 42 will be rolled on to their forward edges. If it is desired to release the paper, it is only necessary to lift the attachment in the manner as shown in Fig. 5. The points 45 and 46 thus are raised out of the paper. When the attachment is in the down position, as shown in Fig. 2, light rays will be projected toward the paper. The opaque covering 47 extends over the greater portion of the tube 14. Since the tube is transparent, light rays pass through the uncovered portion thereof.

In Fig. 7 there is shown a modified form of switch wherein contact terminals 48 and 49 are provided respectively on contact strips 50 and 51. The contact strip 50 is longer than the strip 51, and on the outer end thereof is a projection 52 which extends upwardly and engages with a strip 53 that can be engaged by pencil 42 upon the pencil being extended through the tube 14. The strip 53 is fixed to the tube by a rivet 54.

It should now be apparent that there has been provided an attachment for a writing board which serves not only to effect the lighting of the paper on the board, but also is tiltatable between two positions so as to either release the paper or to hold the paper in position on the board.

It should also be apparent that the attachment is operated by the mere release of the pencil so

that the light automatically is turned on. Upon return of the pencil the light will be turned off. If the light is still on, the user will be given an indication that the pencil needs to be returned. Accordingly, there is little opportunity for the pencil to be lost, and the user of the board will always have such pencil available.

While only one arm 30 is shown to be a spring arm, it will be understood that the other arm 37 can be of the same type. In order that the arm 30 can adapt itself to the board readily, the hole through which the arm 30 extends is tapered. As soon as the attachment is in place on the board, the arm will be centralized in the opening by the spring 35.

While various changes may be made in the detail construction, it shall be understood that such changes shall be within the spirit and scope of the appended claims.

I claim:

1. A writing board lamp attachment comprising a tube adapted to permit the passage of light through the side thereof, a lamp socket secured to the tube, a lamp bulb in the socket, a second tube attached to the side of the first tube and adapted to receive a pencil and serving as a handle for lifting and lowering the attachment, electric circuit means for supplying electric current to said lamp bulb, spring attaching arms extending respectively from the opposite end of the first tube and having hook formation adapted to extend over the edges of the writing board to hold the attachment against upward displacement therefrom, rear leg members projecting respectively from the opposite ends of the first tube and rearwardly of the attaching arms, forward leg members projecting respectively from the first tube and inwardly of the respective and adjacent rear leg members, said forward leg members lying forwardly of the attaching arms and adapted to engage a paper sheet to retain the same in place upon the board as the attachment is lowered forwardly thereunto, said attachment upon being lifted or lowered pivoting on said rear leg members as a pivot.

2. A writing board lamp attachment as defined in claim 1 and said rear leg members respectively having flat bottom faces to hold the attachment in its lifted position against further rearward rotation.

3. A writing board lamp attachment as defined in claim 1 and said electric circuit means including a switch means extending into the second tube and adapted to be operated by a pencil as it is disposed in the second tube.

ARTHUR G. MARSCHAT.
